UNITED STATES PATENT OFFICE.

JUAN LEOPOLDO OTERO, OF LIMA, PERU.

INKSTAND.

No. 903,308.

Specification of Letters Patent.

Patented Nov. 10, 1908.

Application filed January 14, 1908. Serial No. 410,754.

To all whom it may concern:

Be it known that I, JUAN LEOPOLDO OTERO, a citizen of the Republic of Peru, residing in the city of Lima, have invented certain 5 new and useful Improvements in Inkstands; and I do hereby declare the following to be a full, clear, and exact description of the same, such as will enable others skilled in the art to which it appertains to make and 10 use the same.

This invention relates to ink stands, more particularly to a cover for ink stands, and the objects of the invention are to provide means whereby the cover is automatically 15 opened when it is desired to insert a pen in the ink, which upon being removed, the cover automatically closes.

Further objects of the invention will hereinafter appear, and to these ends same consists of means for carrying out the above 20 objects embodying the features of construction, combinations of elements, and arrangements of parts having the general mode of operation, substantially as hereinafter fully 25 described and claimed in the specification and shown in the accompanying drawings, in which:

Figure 1 is a perspective view of my improved ink stand showing the cover closed; 30 Fig. 2 is a perspective view of the ink stand, the cover being open for the insertion of the pen in the ink well.

Referring to the drawings, A represents a suitable base upon which is supported an 35 inkwell B which may be of any desired material or construction, the same being preferably held in position upon the base A by means of the strips C which are secured to the base A around the bottom of the inkwell. 40 The inkwell is preferably secured to the base A so that the same may be readily removed for the purpose of cleaning or refilling. The inkwell is provided with the usual well or cavity D in which the ink is inserted, 45 same being closed by means of a cover E.

It is desirable that the cover E should be kept in position over the well or cavity D when the same is not in actual use, so as to prevent dirt and other material from falling 50 into the ink and also to prevent the ink from evaporating. In order to accomplish the above objects the cover E is suitably pivoted, preferably at its center, to one end of the slotted lever F, the other end of which is 55 pivoted below the slot I upon the pin G which is secured at each end upon the up-

rights H which are preferably situated in the rear of the inkwell B and suitably secured to the base A so as to permit of the inkwell being easily removed. The cover 60 E is operated by means of two curved levers or arms J, the lower ends of which are pivoted to the base A a short distance in the rear of the uprights H. Between the upper ends of the curved lever or arms J is suitably 65 pivoted an operating bar K which is preferably cylindrical and is made of wood, cork or other light material, the same being preferably provided with longitudinal grooves L as shown in the drawings. The curved 70 levers or arms J are operatively connected to the slotted lever F by means of transverse rod M which passes through the slot I in the lever F and is secured at each end to the curved lever or arms J as shown. 75

When the inkwell is closed by the cover E, as shown in Fig. 1, it will be seen that the operating bar K extends over the top of the inkwell in such a manner that the back of the hand will come in contact with the same 80 and simultaneously raise the cover E when it is desired to fill the pen with ink, as shown in Fig. 2. When the pen has been filled with ink, the hand is naturally withdrawn, whereby the operating bar K being unsupported, 85 moves downward, thereby closing the cover E.

To facilitate the operating bar moving downward, the same is made of sufficient weight so as to counterbalance the weight of the cover E, the operating bar K is preferably made as shown in the figure, that is, provided with longitudinal slots, but the same will work nearly as well if the same is not provided with slots and if it is not pivoted, although in the preferred form the 90 operating bar offers very little resistance to the back of the hand when it is desired to fill the pen with ink. The base A may be provided with suitable supports for the purpose of holding pens or pencils as desired. 95 100

While the invention has been described with particular reference to the details of construction, it should be understood that it is not to be limited thereto, as many and various changes, alterations and substitutions may be made therein and still fall within its scope and principle; but 105

What I do claim and desire to secure by Letters Patent is:—

1. An ink stand comprising a cover, a 110 lever one end of which is connected to said cover, and the other end to the top of said

ink stand, arms connected to said lever, said arms being pivoted at one end to said ink stand, and a grooved operating bar pivoted between the other end of said arms and arranged above said inkwell to open and close said cover substantially as and for the purposes set forth.

2. An ink stand comprising a cover, a lever one end of which is connected to said cover and the other end to the top of said ink stand, arms connected to said lever, said arms being pivoted at one end to said ink stand and an operating bar connected between the other ends of said arms and arranged above said ink stand to open and close said cover when the operating bar is moved backward.

3. An ink stand comprising a cover, a slotted lever one end of which is pivoted to said cover and the other end to said ink stand, arms pivoted at one end to said ink stand and an operating bar pivoted between the other ends of said arms, said arms being operatively connected to said slotted lever by means of a rod passing through said slot, substantially as and for the purposes set forth.

In testimony whereof I have signed this specification in the presence of two subscribing witnesses.

JUAN LEOPOLDO OTERO.
